H. Whinfield,
Steam-Boiler Water-Tube.

No 19,669.

Patented Mar. 16, 1858.

Inventor:
Henry Whinfield

UNITED STATES PATENT OFFICE.

HENRY WHINFIELD, OF NEW YORK, N. Y.

STEAM-BOILER.

Specification of Letters Patent No. 19,669, dated March 16, 1858.

To all whom it may concern:

Be it known that I, HENRY WHINFIELD, of No. 6 Wall street, in the city, county, and State of New York, have invented certain 5 Improvements in the Construction of Steam-Boilers; and I do hereby declare that the following is a full, clear, and exact description of the principle or the character which distinguishes it from all other steam-boilers 10 before known and of the manner of making and using the same, reference being had to the accompanying drawings and to the letters of reference marked thereon.

Figure 1— is a section of a boiler with 15 one longitudinal tube or flue connected latitudinally with tubes or flues to the sides and vertically with tubes or flues to the bottom, intended for locomotive engines. Fig. 2— is a section of a boiler with two longitudinal 20 tubes or flues connected latitudinally with tubes or flues to each other and to the sides and also connected vertically with tubes or flues to the bottom. Fig. 3— is a section of a boiler with six longitudinal tubes or flues 25 connected latitudinally with tubes or flues to each other and to the sides and also connected vertically with tubes or flues to the bottom. Fig. 4 is a latitudinal section of Figs. 5, 6 and 9 at (a, a). Fig. 5 is a longitudinal section of Figs. 7 and 8 at (b b) showing the inside of the tubes or flues, fire box, fire water back and descending flue or chimney and box for heating air and water. Fig. 6 is a longitudinal section of Figs. 7 30 and 8 at (c c) showing the outside of the tubes or flues and boxes for heating air and water, with pipes to conduct the heated air into the boiler. Fig. 7— is an elevation of the chimney end of the boiler showing a section through Fig. 5 at (d d) of the box and 35 pipes for heating the air, also receiver and the pipes to conduct the heated air into the boiler. Fig. 8— is an elevation of the front of the boiler showing fire doors, man-hole 40 door, and cleaning places. Fig. 9— is a side elevation of the boiler showing cleaning places, box to heat water and air, and pipes for conducting the heated air into the boiler.

(A), the shell of the boiler—(B) the fire 45 box—(C) the furnace bars—D the vertical water back—(E) the longitudinal tubes or flues—(F) the latitudinal tubes or flues—(G) the vertical tubes or flues—(H) the half tubes or flues—or equivalent forming 50 the bottom of the boiler (I) the flue, chimney or smoke pipe—(J) the damper—(K)

the hot air box—(L) the hot air pipes—(M) the small air pipes—(N) the furnace doors—(O) the man-hole door—(P) the oval holes for cleaning the tubes or flues— 60 (Q) the movable or false bottom for cleaning—(R) pipe from blowing machine or apparatus—(S) the receiver for heated air—(T) the receiver for heating water before injection into the boiler—(U) the 65 ventilating door.

The nature of my invention consists in forming a steam boiler with the usual fire box (B), with one or more or any number of longitudinal tubes or flues (E), latitudinal tubes or flues (F), and vertical tubes or flues (G), all connected together and to the sides, ends, and bottom of the shell of the boiler, as shown in Figs. 1, 2, 3, 4, 5 and 6— 70 in the usual manner as heretofore described; making one of the strongest boilers in use. The importance of this arrangement, is, the non-combustible gases will be separated from the combustible gases, which are, in consequence of the combination and arrangement of all the parts forming the boiler, herein described, retained in said tubes or flues, and consumed as represented in Fig. 5, to wit: the pointed darts represent the light or combustible gases, ascending after 75 separation, which are then and there consumed, causing a great saving in fuel. The round or blunt ended darts represent the heavy or non combustible gases descending 80 down through the vertical tubes or flues (G), into and along the half tubes or flues (H), which represents the bottom of the boiler to the descending flue or chimney (I), which are thereby carried off during the 85 separation of the gases as heretofore described. 90

To insure the most speedy combustion of the gases, I apply a blowing machine or equivalent to force air through the pipe (R), contained in the box (K), which air is 100 there heated; and the heated air is then forced into and through the receiver (S), thence into the pipe (L), and small pipes (M), into the boiler through the latitudinal tubes or flues (F), and thence into the longitudinal tubes or flues (E), and vertical tubes or flues (G), for the purpose of assisting the more speedy combustion of the combustible gases as hereinbefore described and 105 therein contained. By this process the intensity of heat generated is in proportion to 110 the amount of oxygen forced into the boiler

by the blowing machine or equivalent; and consumed; resulting in great economy of fuel, which is the great feature of my invention.

5 The continuous combustion of the gases as heretofore described, in the tubes or flues (E, F and G), during their separation, creates a continual vacuum which causes an increased draft through the fuel in the fire 10 box (B), thereby furnishing a continued supply of combustible gases from the burning fuel to unite with the oxygen of the heated atmosphere forced in through the air pipes (M), and in consequence thereof combustion, thereby generating much more heat with the same quantity of fuel, than can be done with a boiler of any other construction and avoiding any necessity for a blower as now used which so rapidly burns out the fire 15 box and flues over the fire.

I place on the receiver (S), for heated air a regulating valve similar in construction to a steam safety valve for the purpose of increasing or decreasing the volume of heated 20 air forced into the boiler through the small pipes (M). I also place on the boiler two 25 ventilating doors (U), one on each side of the bottom of the chimney (II), as illustrated in Fig. 9 for the admission of cold 30 air, which will greatly assist the operation 35 of the boiler in retaining the combustible gases in the tubes or flues by opening one or both of said doors, and they can also be used to remove any deposit at the bottom of the 40 chimney.

The operation of cleaning the tubes or flues can with great facility be performed through the oval holes (P), on the sides and ends of the boiler, and the dirt or refuse 45 from the tubes or flues will fall through the vertical tubes or flues, onto the ground by first opening the movable or false bottom (Q), which can be replaced with ease.

To enable others skilled in the art to make 5 and use my invention, I will proceed to describe its construction and operation.

I construct my steam boiler of the usual materials in any of the known forms, with a fire box (B), and furnace bars (C), in the 10 usual manner; with a vertical water back (D), extending above the half tubes or flues (H), forming the bottom and a certain arrangement of one or more longitudinal tubes or flues (E), as in Figs. 5 and 6, of any diameter proportionate to the size of the boiler, and connected (when more than one are

used) with one or more or any required number of latitudinal tubes or flues (F), of proportionate size (as in Figs. 1, 2, 3 and 6), to each other, and to the sides of the shell of 60 the boiler (A). The said longitudinal tubes or flues (E), are also connected together with one or more or any required number of vertical tubes or flues (G), of proportionate size to each other, and to the half tubes or 65 flues (H), forming the bottom of the boiler (A), which bottom (H), is formed of longitudinal half circles or half tubes or flues, and inclosed by the movable or false bottom (Q), working or moving on a hinge or joint forming 70 a communication with the flue, chimney, or smoke pipe (I), the damper (J), and the ventilating doors (U), by opening one or both as may be required the combustible gases will be retained in the tubes or flues of 75 the boiler without the constant use of the damper (J), as represented in Figs. 5 and 6.

In the rear of the boiler there is placed a box (K), as wide as the boiler, and extending vertically about half or three-quarters 80 the height of the boiler, which box (K), is heated with the gases from the boiler through the ends of the longitudinal tubes or flues (E), and is constructed as shown in Figs. 6, 7, and 9 and acting as a heater to 85 heat the air passing through the pipes (L) therein contained: to wit: pipe (R), connects with a blowing machine for the purpose of a continual supply of air; which air is heated in the pipes or compartments contained in 90 said box (K), and forced into the receiver (S), thence through the pipes (L), and small pipes (M), or mouth pieces connecting said pipes (L), with the boiler into the longitudinal tubes or flues as herein described. 95

In the rear of box (K), I place a receiver (S), for the purpose of heating water prior to its injection into the boiler by the force pump. Said receiver is heated on one side by the said box (K), and by the chimney or 100 flue (I), passing up through the water in said receiver.

Having thus described my invention, what I claim as new, original, and useful, and desire to secure by Letters Patent is— 105

The arrangement of the longitudinal, latitudinal or transverse and vertical fire tubes or flues as herein set forth.

HENRY WHINFIELD.
